US0D1075826S

(12) **United States Design Patent** (10) **Patent No.:** **US D1,075,826 S**
(45) **Date of Patent:** **** May 20, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Nicholas D. Felton**, Sunnyvale, CA (US); **Mischa McLachlan**, San Francisco, CA (US)

(73) Assignee: **Apple Inc.**, Cupertino, CA (US)

(**) Term: **15 Years**

(21) Appl. No.: **29/893,824**

(22) Filed: **Jun. 2, 2023**

(51) **LOC (15) Cl.** **14-04**

(52) **U.S. Cl.**

USPC **D14/486**

(58) **Field of Classification Search**

USPC D14/485-495

See application file for complete search history.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines depict a display screen or portion thereof, and form no part of the claimed design.
